UNITED STATES PATENT OFFICE.

MARTIN JELALIAN, OF CRANSTON, RHODE ISLAND.

SWIMMING DEVICE.

1,216,457.

Specification of Letters Patent. Patented Feb. 20, 1917.

Application filed July 8, 1916. Serial No. 108,213.

To all whom it may concern:

Be it known that I, MARTIN JELALIAN, a citizen of the United States, residing at the city of Cranston, in the county of Providence and State of Rhode Island, have invented certain new and useful Improvements in Swimming Devices, of which the following is a specification.

This invention is essentially designed for swimming purposes and has for its object to provide a device composed of a buoyant structure adapted to be detachably secured to the body of the swimmer to easily permit the latter to float upon the surface of the water, and provided with propelling means to afford the swimmer to propel himself through the water in a most safe, successful and rapid manner.

The invention consists of the special features of the construction and combination of parts as hereinafter described and claimed.

In describing the invention reference is had to the accompanying sheet of drawings, 25 in which—

Figure 1 is a front view of my improved device showing the same as applied to the body of the swimmer.

Fig. 2 is a front view, showing the parts 30 of the device in their relative position.

Fig. 3 is a rear view showing the parts of the device as in Fig. 2.

Fig. 4 is a side view of a rectangular shaped board as adapted to be secured to 35 the lower part of legs of the swimmer.

Referring to Fig. 1 of the drawings, numeral 1 designates a swimmer. Secured to the abdominal part of the swimmer 1 is a support 2 which is attached by means of 40 straps 5. An air-containing bag 3 carried upon each side of said support is provided with integral main straps near each end thereof as at points —4, 4—. The upper portion of said bag 3 is detachably secured 45 to said support 2 by attaching straps —17, 17— and the lower part thereof attached in a similar manner to a support 9² which is detachably secured to the leg of the swimmer, by means of straps 15; as shown in 50 Figs. 2 and 3.

An air containing bag 3¹ carried upon the shoulders of the swimmer is also provided with main integral straps 5¹. Attaching straps 6 have one of their ends secured to 55 said main straps 5¹ and the other ends attached to the upper portion of the support 2.

The purpose of carrying a bag upon the shoulders of the swimmer is:—that the same will assist the action of the side bags 3, 3— and also keep the head of the swimmer up 60 higher from the surface of the water, when the latter is swimming upon his back or backwardly.

Secured to the hand of the swimmer 1, is a common board 8, which is of a convex- 65 shape in plan view. Said board 8 is provided with securing straps —9, 9— and also a projecting portion 6¹ said portion 6¹, being designed for propelling purposes, pull water when swimming forwardly, and to force the water backwardly when swimming upon his back. Finger securing means are carried upon said projecting portion 6¹ to secure the fingers therein as at 11.

Detachably secured to the lower part of 75 the legs of the swimmer is a common board 16, which is of a rectangular shape in plan view, and is provided with a leg-fitting strap 16¹ and also strapping means as at 18 and 18².

Said board 16, has a projecting portion 6² adapted for propelling purposes, to force the water backwardly when the user is swimming upon his back or backwardly; and it is designed to assist the action of the hand 85 propelling means 8, and also the floating operation of the device.

By this construction and arrangement of parts the swimmer can easily swim several miles in a safe and successful manner; the 90 latter when getting tired can stay upon the surface of the water without moving the parts of his body, and can swim either forwardly or backwardly as may be desired.

In the construction of the supporting 95 structure 2, the latter is provided with an inflating tube connection composed of three parts —16², 16³— which extends centrally from the rear of said support into each of said bags 3 and 3¹ and having suitable valve 100 connections to normally retain the air therein.

Thus describing my invention what I claim and desire to secure by Letters Patent is:—

1. In a device of the character described, a buoyant swimming structure, said structure composed of a support provided with straps for securing to the abdominal part of the swimmer; an air-containing bag carried upon each side of said support and having a main integral strap within and

near to the upper and lower ends thereof; strap connections extending from said upper end main integral straps to said support and attached thereto; similar strap connections 5 extending also from the lower end main straps and attached to a support that is carried upon the upper portion of the leg part of the swimmer and provided with straps for securing thereto.

10 2. In a device of the character described a swimming structure, said structure composed of three supports adapted to be detachably secured to the abdominal and the upper leg parts of the swimmer; air containers carried by said supports and provided with straps for attaching to the latter; an air-containing bag secured upon the shoulders of the swimmer and provided with main integral straps within and near each 15 end thereof; attaching straps having one 20 end of their ends secured to said main straps

and the other ends attached to the upper portion of the abdominal support; an inflating tube connection composed of three parts extending centrally from the rear of said support into each of said bags, and suitable valve connections within each of the same to normally retain the air therein. 25

3. In a swimming device, a body support comprising an abdominal strap and a pair 30 of leg straps, a pair of lateral buoyant members connected at their upper ends to said abdominal strap and at their lower ends to said leg straps, and a buoyant shoulder-member connected to said abdominal strap. 35

In testimony whereof I affix my signature in presence of two witnesses.

MARTIN JELALIAN.
